DESIGN FOR A COFFEE MAKER

Richard I. Felver, Mansfield, Ohio, assignor to Westinghouse Electric & Manufacturing Company, a corporation of Pennsylvania

Application October 24, 1940, Serial No. 96,051

Term of patent 7 years

To all whom it may concern:

Be it known that I, Richard I. Felver, a citizen of the United States, residing at Mansfield, in the county of Richland and State of Ohio, have invented a new, original, and ornamental Design for a Coffee Maker, of which the following is a specification, reference being had to the accompanying drawing, forming part thereof, in which:

front of the coffee maker showing my new design, the concealed rear side of the coffee maker being like the illustrated front side except for the omission of the illustrated pouring lip; and
Fig. 2 is a top plan view of my coffee maker.

I claim:

The ornamental design for a coffee maker, substantially as shown and described.

RICHARD I. FELVER.
